UNITED STATES PATENT OFFICE.

JOHN A. BROOKS, OF DETROIT, MICHIGAN.

SPRINKLING SYSTEM.

Application filed June 12, 1925. Serial No. 36,576.

This invention relates to sprinkling systems, but more particularly to an automatically controlled spraying device for spraying water on lawns, shrubbery and the like.

- Objects of this invention are to provide a sprinkling system automatic in operation and which may be operated at any desired predetermined time; to provide means for automatically increasing the pressure of the liquid supplied to the system concomitantly with the starting thereof; to provide means for automatically stopping the pressure increasing means after a predetermined timed interval; and to provide a sprinkling system having the new and improved features of construction, arrangement and operation hereinafter described.

The invention is shown by way of illustration in the accompanying drawings, in which,—

Figure 1 is a diagrammatic view of the sprinkling system; Fig. 2 is an enlarged side elevation of the motor controlling switch operated by the clock mechanism; Fig. 3 is an enlarged view of the piston and cylinder; and Fig. 4 is an enlarged view of one of the piston heads.

In the illustrated embodiment of the invention the conduit 1 may communicate with any suitable source of liquid supply, for example, the usual city water main, and branching from the conduit 1 may be a conduit 2 for supplying a house with water, a meter 3 being connected to the conduit 1 in the usual manner. Connected to the main supply conduit 1 is a conduit 4 which communicates with a centrifugal force or booster pump 5 for drawing liquid from the main supply conduit 1 through a duct 6. Communicating with the duct 4 is a duct 7 which supplies liquid to the cylinder 8, and connected to the cylinder 8 is a reduced tubular extension 9 which fits into a casting 10 at the opposite end thereof. Leading from the casting 10 is a series of spraying ducts 11, the ends of which are arranged in line and spaced from each other as shown.

For manually controlling the flow of liquid through the spraying ducts 11, valves 12 may be employed, and for draining the liquid from the casting 10 when the device is not in use, an outlet or drain duct 13 is connected to the casting and communicates with a main drain duct 14 leading to any suitable place.

Movable within the cylinder 8 and ex-

tension 9 is a valve member having a main actuating piston 15, fitting in the cylinder 8, a hollow stem 16 and a head having spaced packings 17 in the casting 10. Intermediate 60 the actuating piston 15 and spraying head is a packing 18 which works in the tube 9 and prevents seepage of liquid between the stem 16 and the tube. Liquid from the cylinder 8 passes into the hollow stem 16 65 through perforations 19 and out from the stem 16 through perforations 20 between the packings 17. The packings 17 are sufficiently spaced to bridge one of the outlet openings in the casting 10 leading to a 70 spraying duct 11, and by moving the actuating head 15 longitudinally within the cylinder 8, a liquid successively flows through individual spraying ducts 11.

In order to move the piston to the right 75 of Figure 1, a relatively small duct 21 leads from the branch duct 7 and communicates with the outer end of the cylinder 8. By passing liquid through the duct 21 the pressure at the left of the head 15 will be greater 80 than the pressure on the opposite side of the piston, because on the opposite side of the piston the liquid either flows through the perforations in the stem and passes through one of the spraying ducts 11 or creates an 85 equalized pressure on the packings 17, and in this latter instance the pressure acting to the right against the packing 18 is sufficient to overcome any counteracting pressure.

For controlling the flow of liquid through the duct 21 a valve 22 is employed which may be automatically opened and closed by a clock mechanism 23, which is connected thereto by a cable 24. The clock mechanism 23 may be of any suitable type but preferably is electrically controlled and constructed in such a manner that the cable 24 may be automatically moved in opposite directions at certain predetermined timed intervals. It will thus be apparent that when the valve 22 is opened, liquid forced through the duct 21 by means of the centrifugal booster pump 5 passes into the cylinder 8 and acts against the piston 15 to move the piston to the right and thereby successively 100 supply liquid to the several spraying ducts 11.

The clock mechanism 23 holds the valve 22 open sufficiently for the liquid under pressure to force the piston 15 to the extreme 110 end of the cylinder 8, whereupon the clock mechanism operates automatically to close

the valve 22. In order to enable the liquid pressure at the right side of the piston 15 to move the piston to the left and overcome the pressure at the left side of the piston 15, 5 an outlet duct 25 having a control valve 26 leads from the duct 21 and communicates with the main drain duct 14, the valve 26 being manually adjustable to control the rate of movement of the piston to the left 10 in the cylinder 8. It will be apparent that when the valve 22 is closed the pressure on the right-hand side of the piston 15 is greater than the pressure on the opposite side, so that the piston automatically moves to the 15 extreme left-hand end of the cylinder.

Although any suitable mechanism may be provided for operating the force pump 5, in this instance an electric motor 27 is utilized and the motor 27 is started in operation by 20 means of a switch 28 associated with the cable 24 and controlled thereby. As indicated in Fig. 2, the switch 28 comprises a supporting plate 29, on which is mounted a plate 30, and connected to contact terminals 36 on the plate 30 are leads 31 and 32 from the motor 27. Suitably guided on the plate 30 is a wire 33 carrying a contact arm 34 and upward movement of the wire 33 is 25 yieldingly resisted by a coiled spring 35. The opposite ends of the wire 33 are connected to the cable 24, and it will be apparent that when the cable 24 is lifted by the mechanism 23 to open the valve 22, the contact arm 34 is moved into engagement with 30 the contact terminals 36 on the plate 30, thereby to close the circuit and start the motor. After the piston 15 has been moved to the extreme right end of the cylinder 8 the valve 22 is closed, and in this movement 35 the cable 24 is released or moved downwardly whereby the coiled spring 35 moves the arm 34 away from the contact piece 36.

In order to insure the continued operation of the motor 27 after the valve 22 has 40 been opened and to maintain the motor running after the contact arm 34 has been moved away from the contact terminals 36 thereby to return the piston 15 to the opposite end of the cylinder 8, a switch 37 45 communicates with the motor leads 31 and 32 by leads 38 and 39, respectively and is provided with a substantially V-shaped circuit closing element 40 which is pivotally connected to the switch and projects outwardly therefrom. For actuating the circuit closing element 40 a rod 41 is connected to the piston 15 and extends through a guide 42 connected to the outer end of the cylinder 8, an actuating knob 43 being formed 50 on the outer end of the rod 41 for engagement with the element 40.

When the piston 15 is in its extreme left-hand position in the cylinder 8, the knob 43 has engaged one of the arms of the circuit closing element 40 and moved this ele-

ment to open the circuit, but after the piston 15 has been moved a slight distance to the right within the reservoir the knob 43 releases the element 40 and enables this element to assume (by means of any suitable 70 mechanism within the switch box as a spring arrangement) its normal circuit closing position so that the motor continues in operation until the cycle is completed. It will be apparent that thereafter the knob 43 engages the element 40 to move this element to the left, thereby to open the circuit and shut off the motor 27.

Under some circumstances, it may be desirable to control the operation of the motor 27 by hand, and for this purpose a manually operable switch 44 is connected to the leads 31 and 32 substantially as indicated.

From the above description it will be apparent that the time clock 23 may be set to 85 operate at a certain predetermined time and when this time arrives the valve 22 will automatically be opened. Concomitantly with the opening of the valve 22 the switch 28 is closed to energize the motor 27 thereby operating the booster pump 5 to increase the pressure of the liquid supplied to the cylinder 8. A portion of the liquid from the pipe 7 passes to the left hand side of the piston 15 through the smaller pipe 21, and the pressure of this liquid is great enough to overcome the pressure of the liquid on the opposite side of the piston thereby moving the piston to the right within the cylinder 8.

As the piston 15 moves to the right within the cylinder liquid entering the hollow bore of the stem 19 through perforations 16 passes successively into the conduits 11 through the perforations 20 between the packings 17. A system of this character is particularly useful for spraying lawns and the like and for this purpose the conduits 11 may lead to spraying heads which are positioned at suitably spaced intervals in the ground or wherever desired.

As heretofore pointed out movement of the piston 15 to the right disengages the knob 43 carried by the rod 41 from the switch actuating element 40, thus enabling the switch 37 automatically to close the circuit included by the leads 38 and 39 and thereby energizing the motor. The time clock mechanism 23 may operate for a period sufficient for the piston 15 to have moved to the extreme right within the cylinder 8 and thereupon the clock mechanism operates automatically to close the valve 22, and open the switch 28. Thereafter the motor 27 is maintained in operation by 115 means of the circuit controlled by the switch 37.

Upon closing the valve 22, the pressure on the left-hand side of the piston 15 is sufficiently reduced for the pressure on the 120 right hand side of the piston to move the 125 piston to the left, thereby to open the valve 22, and close the switch 28. Thereafter the motor 27 is maintained in operation by the switch 37.

- piston to the left within the cylinder 8. In this movement of the piston, it will be clear that liquid may flow successively through the spraying conduits 11 in reverse order.
- 5 The movement of the piston 15 to the left within the cylinder 8 continues until the knob 43 engages the switch actuating element 40 and moves this element to open the circuit and thereby shut off the pump operating motor and discontinue the operation of the system.
- 10 While I have shown and described an arrangement and construction which is the best known to me at the present time, it is to be understood that numerous changes in details of the arrangement, construction and operation may be effected without departing from the spirit of the invention, especially as defined in the appended claims.
- 15 20 What I claim and desire to secure by Letters Patent is:—
1. In a sprinkling system having a plurality of spraying conduits, a cylinder, valve means for successively controlling the passage of liquid from the cylinder to individual conduits, a main duct for supplying a liquid to said cylinder adjacent one end thereof, a duct for supplying liquid to the opposite end of said cylinder for actuating said valve means in one direction, a valve for controlling the flow of liquid through said last mentioned duct, mechanism for operating said valve, and an outlet duct branching from said last mentioned duct, 25 and a valve in said outlet duct for controlling the liquid flow therethrough.
2. In a sprinkling system having a plurality of spraying conduits, a cylinder, valve means for successively controlling the passage of liquid from the cylinder to said conduits, a main duct for supplying liquid to said cylinder adjacent one end thereof, a duct for supplying liquid to the opposite end of said cylinder for actuating said valve means in one direction, a valve for controlling the flow of liquid through said last mentioned duct, mechanism for opening and closing said valve in said last mentioned duct for controlling the liquid flow there- 30 through, a pump for increasing the pressure of the liquid supplied to said ducts, a motor for operating said pump, means controlled by said opening and closing mechanism for starting said motor, and means controlled by said valve means for stopping said motor.
- 35 40 45 50 55 60 65 70 75 80 85 90 95 100 105 110 115
3. In a sprinkling system having a plurality of spraying conduits, a cylinder, valve means for successively controlling the passage of liquid from the cylinder to individual conduits, a main duct for supplying
- liquid to said cylinder adjacent one end thereof, a duct for supplying liquid to the opposite end of said cylinder for actuating said valve means in one direction, a valve for controlling the flow of liquid through said last mentioned duct, mechanism for opening and closing said valve at predetermined intervals, an outlet duct branching from said last mentioned duct, a valve in said outlet duct for regulating the liquid flow therethrough, means for increasing the pressure of the liquid supplied to said ducts, a motor for operating said pressure increasing means, means operable by said opening and closing mechanism for starting said motor, and means independent of said starting means for stopping said motor.
4. In a sprinkling system having a plurality of spraying conduits, a cylinder, valve means for successively supplying liquid from the cylinder to individual conduits, a main supply conduit for feeding liquid to said cylinder adjacent one end thereof, a duct for supplying liquid to the opposite end of said cylinder for actuating the valve means, automatic means for controlling the liquid flow through said duct, a pump for increasing the pressure of liquid supplied to both said conduit and duct, a motor for operating said pump, means for starting said motor in timed relation to said automatic means, and means controlled by said valve means, for stopping said motor after a predetermined time interval.
5. In a sprinkling system, a cylinder, a tubular extension on said cylinder, said extension communicating with a plurality of individual spraying ducts, a piston having a main head movable in said cylinder, a tubular stem, and a smaller head movable in said extension, said smaller head having spaced packing members and perforations between said members, said stem having perforations in the region of said main head, means for supplying liquid to said cylinder at the end adjacent said extension, a duct for admitting liquid to the opposite end of said cylinder to move said main piston toward said extension, said duct communicating with the main source of liquid supply, an outlet duct communicating with said admission duct, and means for controlling the flow of liquid through said admission duct, whereby the piston is driven to the opposite end of the cylinder and liquid flowing through the stem successively passes through said spraying ducts.
- In testimony whereof I have hereunto signed my name to this specification.

JOHN A. BROOKS.
